JOHN BLACKWOOD AND THEODORE C. WILSON, OF CINCINNATI, OHIO.

Letters Patent No. 69,167, dated September 24, 1867.

IMPROVEMENT IN HAND-SPINNING MACHINE.

The Schedule referred to in these Letters Patent and making part of the same.

TO ALL WHOM IT MAY CONCERN:

Be it known that we, JOHN BLACKWOOD and THEODORE C. WILSON, of Cincinnati, in the county of Hamilton, and State of Ohio, have invented a new and useful Improvement in Hand-Spinning Machines; and we do hereby declare that the following is a full, clear, and exact description thereof, which will enable others skilled in the art to make and use the same, reference being had to the accompanying drawings, forming part of this specification, in which—

Figure 1 is a vertical longitudinal section in the line $x x$, fig. 2, of our improved spinning machine.

Figure 2 is a plan view, and

Figure 3 is a detached sectional view of the two loose pulleys on the vertical driving-shaft.

Similar letters of reference indicate like parts.

This invention relates to a new and useful improvement in the construction of hand-spinning machines for wool and other fibre, and consists in the arrangement of mechanism for operating with a crank upon two or more spindles set in the arc of a circle with one pulley-band, which dispenses with intermediate tightening pulleys, and in connection therewith a reciprocating feed-carriage.

The advantages of these improvements are, cheapness in the construction of the machine, simplicity of the machinery, which performs good work, without liability to get out of order, while it is easily managed, and requires but little power to operate it.

A represents a long oblong frame made of wood, and firmly bolted together. On the top rails $a a$ of the frame are mounted a reciprocating carriage and table, B , provided with two feed-rolls, $b b'$. The shaft of the lower roll b projects at one end, and carries on its outer end a pinion, c , that works in a rack, d , for giving the feed-motion. The rack d is placed on a long lever, C , pivoted at the rear end of the frame of the machine in such manner that when the front end of the lever is depressed by the operative bearing on the handle d' , the rack engages in the pinion c , and lies horizontally, so that the pinion works freely in it the whole length of the rack. On the front end of the machine any convenient number of spindles $e e$ is set on the rails $g g'$, in the arc of a circle, and are actuated by a single band, e' , running over all of them, from a large horizontal driving-pulley, D , on the vertical shaft h , which takes motion by means of the bevel-gear k from the horizontal driving-shaft m , that is turned by the crank n in front of the spindles. On the upper end of the shaft h are two loose pulleys, $s s'$, which pass through a slot, i , in a lever, p , that is pivoted at one end to the side of the frame A , and fastened at the other end to the long rack-lever C . Projecting pins $r r'$ are inserted in the vertical shaft h above and below the loose pulleys $s s'$, which have one or more projections or teeth, $q q'$, on their upper and lower sides, respectively, for striking the pins $r r'$, and turning the pulleys alternately with the shaft h , when the slotted lever p raises and lowers the loose pulleys as it is elevated or depressed by the movement of the rack-lever C , to be hereinafter explained. Bands $w w$ pass around the loose pulleys $s s'$ and $u u$ at the rear of the machine, and are fastened to the under side of the carriage B at y in such a manner that they draw the carriage by the rotation of the loose pulleys backward and forward, alternately. When the depression of the slotted lever p takes place, the lower loose pulley s is pressed down on the shaft h so that the pin r strikes the tooth and rotates the lower pulley, by which the carriage B is drawn back on the ways; and when the lever p is elevated it raises the upper loose pulley s' , till the pin r' strikes the projection q' , and draws the carriage forward, and thus the carriage traverses back and forth when the machine is in operation.

The operation is as follows: When the carriage and table B are in position at the forward end of the table, and the rolls or roping of wool are laid upon the table, their ends are passed between the feed-rolls, to be twisted a few times around the spindles; the long lever C is then depressed to the lower notch or shoulder z , which engages the rack d with the pinion c , and at the same time depresses the slotted lever p , and thus engages the lower pulley s with the pin r on the vertical shaft h ; the crank n is then turned, giving simultaneous motion to the carriage, the feed-rolls, and the spindles. When the carriage reaches the rear of the machine the long lever C is raised to the middle notch z' , when the loose pulleys both become inoperative and the carriage stands still. The crank continues to turn till the yarn is twisted enough, and then the long lever C is elevated to the upper notch z^2 , which raises the slotted lever p and the loose pulley s' to engage the pin r' and tooth q' , and thus reverse the motion of the carriage towards the front of the machine. The pinion c and the rack d are at this time disengaged, and the feed-rolls are consequently inoperative.

Having thus described our invention, what we claim as new, and desire to secure by Letters Patent, is—

1. The loose pulleys s s' on the shaft h , in combination with the slotted lever p , the long lever C , the pulleys u u , bands w w , and the carriage B , arranged and operating substantially as and for the purposes described.
2. The combination of the feed-rolls b b' , the pinion c , the rack d , the slotted lever p , the pulleys s s' , and the carriage B , arranged and operating substantially as set forth.

JOHN BLACKWOOD,
THEODORE C. WILSON.
